BY Richard Oliver,

ATTORNEY

UNITED STATES PATENT OFFICE.

MILDRED C. O'BANNON, OF CULPEPER, VIRGINIA.

COMBINATION LEGGING AND RETAINING-HOOK THEREFOR.

1,285,337.

Specification of Letters Patent. Patented Nov. 19, 1918.

Application filed September 6, 1917. Serial No. 190,026.

To all whom it may concern:

Be it known that I, MILDRED C. O'BANNON, a citizen of the United States, residing at Culpeper, in the county of Culpeper and 5 State of Virginia, have invented certain new and useful Improvements in Combination Leggings and Retaining-Hooks Therefor, of which the following is a specification.

This invention relates to legging hooks, 10 and to a device of this character for use upon leggings or gaiters to hold the front portion of the same in a neat and snug fit over the instep, and to retain the material of the legging or gaiter against wrinkling. 15 An object of my invention is to provide a hook which can be embedded in the legging or gaiter as the same is manufactured, or which may be sold as a separate part to be applied by the wearer, and which hook 20 is of such construction that when mounted in combination with the legging or gaiter, the forward part of the same will be held in a smooth fit over the arch of the foot against shoving up to expose the laces of 25 the shoe.

A further object resides in so constructing the hook that it can be readily embodied with the structure of a legging or gaiter and when secured in place thereon will not 30 unduly draw or strain the structure or cause the same to pull and wrinkle.

With the above and other objects in view, which will be in part described and in part understood from the specification, drawings, 35 and claims, my invention consists in certain novel features of construction and combination of parts which will be hereinafter more fully set forth.

In the drawings:—

40 Figure 1 is a view showing a legging having the structure of my invention embodied therewith as the same would appear when fitted for use;

Fig. 2 is a detailed view showing a fragmentary portion of a legging or gaiter with the hook mounted in place thereon;

Fig. 3 is a sectional view on the line 3—3 of Fig. 2; and,

Fig. 4 is a detailed sectional view through 50 the hook to better show the manner of hooking the same and of providing for securing thereof to a legging or gaiter.

In the present illustration I have shown the hook applied to a relatively short legging and have disclosed the hook as being 55 caught around one of the lengths of the lac-

ing of a shoe of the lace type, although as the description progresses, it will be apparent that my invention is of such character that it is equally well adapted for 60 use upon button shoes.

The hook proper is preferably made of a blank of a spring sheet metal which is cut to form a base portion 1 and a bill 2, that portion of the hook between the base and 65 the bill being preferably narrowed down as shown at 3. In making up cloth leggings and gaiters, it is customary to form a seam substantially down the middle of the forward extension portion thereof, and to tape 70 this seam, substantially as is shown in Figs. 2 and 4, and as the hook is particularly adaptable for use in holding this forward extension against pushing and rolling up, it is preferable that provision be made for 75 the securement of the hook so that it will be attached entirely upon the seam and will not have securement to the main body of the material of the legging or gaiter. With this purpose in view, I provide the 80 openings or eyes 4 at the free end of the base portion 2, which openings or eyes are preferably placed in the middle portion of the base portion so that as stitching is passed therethrough and through the structure of 85 the gaiter, all of the stitches can be caught into the taped seam of the gaiter or legging. In the base portion 1 the openings or eyelets 5 are provided adjacent the other extremity, and stitching can be passed there- 90 through and into the taped seam, substan- tially after the manner shown in Fig. 4.

In some uses, it might be found desirable to attach the hook to, or adjacent to, the lower edge of a puttee, to hold the same 95 against shifting above the top of a shoe, and it will of course be understood that this could be done by passing stitching or other suitable fastening through the openings or eyelets 4 and 5. In use, it will of course 100 be understood that the hook will be located at such a point that it will catch beneath the lacings of the shoe, substantially as shown in Fig. 1 of the drawings, or in the case of a button shoe, it will catch on the 105 edge of the closing flap, and in any of the uses as suggested, it will be appreciated that the foot will not only hold the parts of the leggings, gaiter, or puttee, against shifting above the shoe, but that in the case of a 110 legging or gaiter, the forward part will be held to fit smoothly over the arch of the

foot. By bringing the base and bill portions together at the fold, substantially as shown in Fig. 3, the parts will exert a gripping action upon the part around which they are placed to hold, and the tendency will be not only to hold the legging or garter against shifting up, but also to retain the same against slipping down. Where the hook is caught around a length 10 of the lacing, it is perhaps preferable that at the sides the folded portion be rounded substantially as shown at 6, in Fig. 4, and where this shaping is resorted to a smooth rounded surface will be presented at the 15 edge where the hook would otherwise bear upon the lacing, and in consequence the lacing is protected against excessive wear.

While I have herein shown and described the hook as constructed in one specific manner, and have set forth only certain ways in which the same would be fitted for use, it will of course be understood that changes and variations might be made in the construction of the hook and in the manner of 25 using the same, and hence I wish to be limited only to such points as may be set forth in the claims.

I claim:

1. In combination with a legging comprising a flared lower end adapted to fit snugly over the upper of a shoe, a hook secured to the forward end of said legging near the lower edge thereof and adapted to firmly engage the lace of a shoe and prevent 30 the front end of said legging from curling upwardly and also firmly hold the same in close engagement with the vamp of the shoe.
2. In combination with a legging pro-

vided with a flared lower end adapted to fit snugly over the upper of a shoe, a flat hook 40 secured to the under face of said legging and arranged for engagement with the lower edge of a closure flap of a shoe.

3. In combination with a legging adapted to fit snugly around the upper of a shoe and 45 having its lower edge shaped to conform to the contour of a shoe, said legging provided with a reinforcing strip formed centrally thereof upon the under face, a flat metal hook secured to said reinforcing strip 50 and provided with a bill extending substantially parallel with said reinforcing strip and being contracted, said bill adapted to engage the lace of a shoe and firmly hold the forward end of said legging in a position to overhang the upper edge of the vamp 55 of the shoe.

4. In combination with a legging, a hook made of a single piece of sheet metal shaped to produce a base portion for facilitating 60 the attachment thereof to the under face of said legging, said base portion being contracted to produce a shoe engaging portion, said contracted portion terminating in a projecting bill extending substantially parallel with said base portion, and said bill 65 adapted to firmly engage a portion of a shoe for firmly holding the forward end of said legging in close engagement with the upper edge of the vamp of the shoe.

In testimony whereof I affix my signature in presence of two witnesses.

MILDRED C. O'BANNON.
